UNITED STATES PATENT OFFICE.

JOSEPH VAN ACKEREN, OF PITTSBURGH, PENNSYLVANIA, ASSIGNOR TO THE KOPPERS COMPANY, OF PITTSBURGH, PENNSYLVANIA, A CORPORATION OF PENNSYLVANIA.

VERTICAL RETORT BATTERY.

Application filed February 4, 1921, Serial No. 442,357. Renewed June 3, 1924.

To all whom it may concern:

Be it known that I, JOSEPH VAN ACKEREN, a citizen of the United States, residing in Pittsburgh, in the county of Allegheny and State of Pennsylvania, have invented a new and useful Improvement in Vertical Retort Batteries, of which the following is a specification.

This invention comprehends improvements in the art of vertical retorts, and has for an object the provision of a vertical retort that is highly efficient in operation and which will produce high grade coke suitable for metallurgical use and effect a substantially complete by-product recovery, although the entire distilling operation is conducted rapidly, in fact within a considerably shorter period of time than heretofore accomplished, and with great conservation of heat.

Important characteristics of the invention are the provision of a system of combustion in the flame or combustion flues of the heating walls of the retort chambers, by which system flame or combustion is maintained continuously in all of the flues of each heating wall; the combination of this improved system of combustion with a complete reversible regenerative system for conserving the waste heat from the combustion flues and imparting such heat to the medium fed into such flues; the attainment of an extreme flexibility in operation exemplified in the ready adaptability for operation of the retort for operation alternatively with an extraneously derived gas, such as producer gas, for fuel, or with the gas produced from the distillation of the coal within the retort chambers, combined with the provision of means for changing at will the oven into one or the other of its several modes of operation; the attainment of great efficiency of combustion within the flame flues of the heating walls, notwithstanding the fuel employed, such efficiency being exemplified in an even distribution of the heat over the area of the heating walls and the prevention of flame concentration in said walls.

In addition to the general objects recited above, the invention has for other objects such other improvements or advantages in construction and operation as are found to obtain in the structures and devices herein-after described or claimed.

In the accompanying drawings, forming

a part of the specification, and showing, for purposes of exemplification a preferred form and manner in which the invention may be embodied and practiced, but without limiting the claimed invention specifically to such illustrative instance or instances:

Figure 1 is a vertical sectional elevation of a vertical retort embodying features above specified and constructed in accordance with the improvements of the present invention, the view being taken in a vertical plane indicated by the line B—B of Figs. 2 and 4;

Fig. 2 is a vertical sectional elevation of the same taken in a plane indicated by the line A—A of Figs. 1 and 4;

Fig. 3 is another vertical sectional elevation of the same taken in a plane indicated by the line C—C of Figs. 2 and 4;

Fig. 4 is a composite horizontal sectional elevation of the same taken in different horizontal planes indicated by the lines D—D, E—E, F—F and G—G of Fig. 1;

Fig. 5 is another horizontal section of the same taken in the horizontal plane indicated by the line H—H of Fig. 1;

Fig. 6 is a top plan view of the retort battery; and,

Fig. 7 is a bottom plan view of the same.

The same characters of reference indicate the same parts in each of the several views of the drawings.

In its present embodiment, the invention is incorporated in a retort of the vertical type and, for convenience, the present description will be confined to this use of the invention; features of construction and operation are, however, capable of other valuable applications and consequently the scope of the invention is not confined to the specific use and specific embodiment herein described as an illustrative example.

Referring to the drawings, there are illustrated views of a vertical retort of the by-product type, as hereinbefore mentioned, which embodies in its construction a plurality of intermediate vertically elongated retorts or coking chambers 12, 12, the heating walls and the retort chambers extending to a great height as compared with their respective widths and with the crosswise dimension of the retort battery. The heating walls 11 form the side walls of the respective retort chambers 12, as shown, and the opposite ends of the respective retort cham-

bers, as well as the heating walls are closed and reinforced by side refractory walls designated generally by the reference characters 13, 13. Beyond these side refractory walls 13, 13 and extending along the opposite sides of the retort battery and from top to bottom thereof are located wall and chamber constructions utilized for the regenerators and other parts hereinafter described.

The coal to be coked is charged into the retort chambers 12 through charging holes 14 located in the top of the retort and the finished coke is discharged through discharge openings 15 at the bottom of such retort chambers. In order to facilitate discharge of the coke from said retort chambers, the side walls of the retort chambers diverge toward the bottom thereof, as shown more particularly in Fig. 2. Because of the great height of the retort chambers as compared with their width and crosswise dimension, the retort battery may be utilized as a continuous vertical retort. When so used, the charging holes 14 are left open and also the discharge openings 15, to permit the continuous charging of the coal to be coked and the continuous discharge of the finished coke.

Heat for coking the charges of coal in the several retort chambers 12 is derived from the heating walls 11 above mentioned. Referring now more particularly to Figs. 1 and 4, each heating wall 11 is constituted of a plurality of vertical combustion flues 16 that are operatively disposed into two groups I and K, the groups I of the several heating walls being on one side of the central longitudinal partitions 17 of such walls and the groups K being on the other side of these partitions. While the flame flues of the several groups I, on one side of the partition 17 are burning downwardly, that is to say, operating for downflow, the several groups K of flame flues on the opposite side of the aforesaid partitions 17 are burning upwardly or operating for upflow. Reversal of the retort battery is effective to cause the groups I of heating flues to burn upwardly and concurrently the groups K of such flues to burn downwardly.

The regenerators 18 are incorporated in the structures which extend longitudinally along the retort battery at the opposite ends of the retort chambers 12 and the heating walls 11, and, in the present instance each regenerator extends vertically from a plane above the bottom horizontal plane of the heating walls to a plane above the top horizontal plane of such walls. As shown in Fig. 5, the several regenerators of a retort battery are disposed into two series I' and K' that are respectively located on opposite sides of the battery. One series I' of such regenerators corresponds with and

is communicably connected with the flues of the groups I, and the other series K' of the regenerators corresponds with and is communicably connected with the several flues of the groups K. Each series of such regenerators is, moreover, grouped into pairs, the alternate pairs of each series of regenerators being respectively designated by the reference character L and the intermediate pairs of each said series being respectively designated by the reference character M. Each such pair of regenerators is separated from the other contiguous pair by means of a heavy vertical gas tight wall 19, and the individual regenerators of each pair are separated from each other by means of a vertical gas tight partition 20.

Each regenerator 18 is a chamber containing open brickwork, commonly called checkerwork, and indicated at 21 with sole channels 22 underneath such checkerwork, the channels forming the soles of such chambers and opening up into the checkerwork. The several regenerators are heated, in alternation, by the hot combustion products that are exhausted from the flame or combustion flues hereinbefore mentioned and then impart such heat to the medium that they feed into these flame flues.

As shown in Figs. 1 and 5 the upper portion of each regenerator 18 opens up into a cross channel 23, that extends over the flues of the group corresponding to that regenerator and communicates with the respective flues of such group by means of ports 24 connecting the individual flue 16 with such channel. The channels 23 of the two series I' and K' of regenerators respectively extend inwardly toward each other and, the channels of one series of regenerators are separated from the channel of the other series by means of the central vertical partition 17 of the heating walls. The channel 23 of one member of each group I' of a series of regenerators communicates with a single contiguous group of combustion flues corresponding to that series of regenerators, and the channel 23 of the contiguous regenerator of the next adjacent group M leads to and communicates with the combustion flues of the same group of the same heating wall. According to this arrangement, each group of combustion flues is connected by a pair of channels 23 with two regenerators of the corresponding series, the regenerators so connected with the same group of combustion flues being respectively positioned on opposite sides of a heavy partition wall 19. The advantage of this will be clear in the hereinafter described operation of the battery.

In the present embodiment of the invention, the groups of flues I on one side of the battery operate for flow in one direction, while concurrently the groups of flues K on

the other side of the battery are operating for flow in the opposite direction, consequently there is maintained flow in reverse directions through the regenerators that are 5 respectively positioned on opposite sides of the battery. The reversal in flow through the flame flues and their communicably connected regenerators may thus be said to take place crosswise of the battery and such 10 reversal is effected at the end of an operating period determined by practice by means of any preferred type of reversing mechanism parts of which are illustrated in the accompanying drawings and will be herein- 15 after described. The function of such reversal is as follows: The regenerators that prior to the reversal operated as inflow regenerators become outflow regenerators, and the outflow operating regenerators become 20 inflow operating regenerators; the upburning groups of flues switch functions with the downburning groups of flues on the opposite side of the battery.

At the bottom of each heating wall, there 25 is located a horizontal or bus flue 25, said flue 25 being in communication with all of the flame flues 16 of its respective heating wall. With this construction, the lower ends of the flame flues of the group I of 30 each heating wall communicate with the lower ends of the group K and consequently the downflow from one of said groups of flame flues may pass into and upwardly through the other.

35 In the top of each heating wall 11 there is provided a series of vertically extending gas ducts 26, which respectively communicate with the upper ends of the individual flame flues 16 of the respective heating wall. 40 Each such gas duct 26 is provided with a suitable nozzle 27 the discharge end of which opens up into a small chamber 28 that is adapted to function as a mixing chamber, as will hereinafter appear, and 45 communicates through a port 29 with the top of the corresponding flame flue. As shown in Fig. 2, the chamber 28 above each flue is disposed between the two ports 24 which connect such flue with the channels 50 23 hereinbefore mentioned.

Extending through the bottom of each heating wall 11 is a series of gas ducts 30, the individual members of which individually communicate with the lower ends of the flame flues 16 of the corresponding heating wall. The several ducts 26 and 30 are for the purpose of supplying the gas formed by the distillation of coal in the retort to their respective connected combustion flues, 55 when such gas is the medium employed as fuel. Any suitable mains may be provided for conveying the gas to such series of ducts 26 and 30.

As shown more particularly in Figs. 1 60 and 5 long vertical channels 31 respectively

extend downwardly from the top horizontal channels of alternate pairs of regenerators, such as the groups L of the series I' and the groups M of the series K', and said vertical channels 31 merge at their respective lower ends into horizontal channels 32 located beneath the horizontal channels or bus flues 25 that connect the several flues 16 of the respective heating walls. Each said horizontal channel 32 is provided with 70 ports 33 which open up into the before mentioned horizontal channel 25 beneath the flues of the group on the opposite side of the central longitudinal partition 17 to that of the regenerator 18 with which such horizontal channel 32 is connected through the medium of the intermediate vertical channel 31. With this construction, the alternate groups L of regenerators of the series I' are communicably connected by channels 80 and ports with the lower ends of several flues of the groups K, whereas the intermediate groups M of regenerators of the series K' are communicably connected by similar channels and ports with the lower 90 ends of the several flues of the groups L.

The lower end of each flue of both groups I and K is communicably connected with a long vertical channel 34 which extends upwardly above the flue and communicates 95 with the mixing chamber 28 above that flue by means of a port 35. These vertical channels 34 and their ports 25 are for the purpose of effecting return of a portion of the waste gases from the bottoms of downflow 100 operating flues to the chambers 28 above such flues in order to supply to the fuel gas delivered to such chambers a neutral gaseous diluent which has the effect of lengthening the flame in the downburning flues as will hereinafter appear in the detailed description of the operation of the retort battery.

Extending longitudinally of the battery 110 respectively beneath the regenerators of the series I' and K' are waste gas tunnels 36 and 37. The waste gas tunnel 36 that corresponds to the series I' of regenerators is connected with the sole channels 22 of the respective regenerators of said series by means of flow pipes 38; the waste gas tunnel 37 of the series K' of regenerators is connected with the sole channels 22 of the respective regenerators of said series by means of flow pipes 39. As hereinbefore stated, 115 when one series of said regenerators is operating for upflow to deliver preheated medium to the flues, the other series of said regenerators is operating for downflow to heat the checkerwork for the purpose of heating the medium introduced into the regenerators on subsequent reversal. Consequently, whenever a series of regenerators 120 is operating for downflow, all of the regenerators of that series are connected with the 125

130

waste gas tunnel and the upflow operating series of regenerators are shut off from the waste gas tunnel. For this purpose, there is provided in each flow pipe of the series 5 38 a mushroom valve 40, and in each flow pipe of the series 39 a mushroom valve 41. The several mushroom valves 40 are respectively provided with valve operating levers 42 and the several mushroom valves 41 are 10 also respectively provided with valve operating levers 43. A cable of the usual type is provided for operating in unison the several valve operating levers of the series 42, and a similar cable is provided for operating 15 in unison the several valve operating levers of the series 43. This construction permits all of the regenerators of one series to be placed in communication with the waste gas tunnel while concurrently cutting 20 off all of the regenerators of the other series from communication with the waste gas tunnel corresponding to the regenerators of that series.

Arranged longitudinally along that side 25 of the battery of the I' series of regenerators and corresponding thereto is a series of air inlet ports 44; on the opposite side of the battery there is another series of air ports 45 corresponding to the K' series of 30 regenerators. The above mentioned series 44 comprises air ports corresponding in number to the pairs of regenerators of the series I'; these ports 44 respectively extend upwardly from the bottom of the battery 35 and communicate with horizontal channels 46 which respectively extend around the bottom of the corresponding heating walls, as shown in Fig. 4, and thence each communicate with two vertical channels 47 which respectively lead into the sole channels 22 of 40 the regenerators of the series I'. The series 45 also comprises a number of air ports extending upwardly from the bottom of the battery and communicating at their upper 45 ends respectively with similarly surrounding air channels 48 which are located beneath the channels 46 aforesaid and respectively each communicate with two vertical air channels 49 that lead individually to 50 the sole channels 22 of the regenerators of the series K'. The sliding bricks 50 positioned in the bottoms of the sole channels 22 of the regenerators of the series I' control the flow from the vertical channels 47; 55 similarly positioned sliding bricks 51 in the regenerators of the series K' control the flow from the vertical channels 49.

Extending along that side of the battery 60 of the regenerators of the series I' and corresponding thereto is a producer gas main 52 provided with valve controlled flow pipes 53 which are respectively connected with the flow pipes 38 of the regenerators of that series. On the opposite side of the battery is 65 another producer gas main 54 provided with valve controlled pipes 55 which lead to the flow pipes 39 of the series K' of regenerators.

Referring more particularly to Figs. 1 to 3 inclusive, each of the flues 16 may be 70 reached through access channels 56 which extend from the horizontal channels 23 to the top of the battery. These access channels 56 are positioned in pairs over the flues 16, as shown in Fig. 2. Similar access channels 75 57 afford communication to the long vertical channels 34, and additional access channels 58 are provided for permitting communication to the long vertical channels 31. Sliding bricks 59 control the flow 80 through the ports 24 of the flues 16 and through the long vertical channels 31.

As hereinbefore stated, one of the important features of the invention is the attainment of an extreme flexibility in operation of the retort battery, permitting a ready adaptability of the battery for operation either with an extraneously derived gas, such as producer gas for fuel or with the retort 85 gas derived from the distillation of coal in the coking chambers of the retort battery. These ends are attained, with a maximum efficiency of combustion and heat conservation whichever gas is employed as fuel, by the incorporation in a retort battery of 90 structural features and a flexible system of control, such as has been described in connection with the present embodiment of the invention. A number of important advantages and improvements made by the invention 95 can, however, best be pointed out by tracing out separately the operation of the invention, as exemplified in the accompanying drawings, according to its several different modes of operation.

The operation of the retort battery, when using a relatively lean special generator gas, such as ordinary producer gas, for fuel is as follows: The supply of retort gas to the mains supplying the gas ducts 26 and 30 is 100 shut off and a supply of producer gas is permitted to flow into the producer gas mains 52 and 54. Assuming that the several regenerators comprising the series I' are operating as inflow regenerators and that the flues of the groups I are operating as down-burning flues, whereas the regenerators of the series K' and the flues of the groups K are respectively operating as 105 down-flow regenerators and upburning flues, as above described, it follows that during this period of an operation alternate regenerators of the series I' are utilized for preheating the producer gas which is subsequently introduced into the flues. The 110 regenerators intermediate such alternate regenerators of the same series are concurrently utilized for preheating the air to support the combustion of the producer gas, whereas all of the regenerators of the series K' are operating as upburning flues.

Extending along that side of the battery of the regenerators of the series I' and corresponding thereto is a producer gas main 52 provided with valve controlled flow pipes 53 which are respectively connected with the flow pipes 38 of the regenerators of that series. On the opposite side of the battery is another producer gas main 54 provided with valve controlled pipes 55 which lead to the flow pipes 39 of the series K' of regenerators.

ries K' operate to convey the waste gases to the exhaust tunnel 37 connected with such series of regenerators. In adjusting the retort battery for operation with the special generator gas as fuel, the sliding bricks 50 of the alternate pairs L of regenerators of the series I' are moved to close the discharge ends of the vertical air channels 47 which lead into such regenerators, whereas 5 the sliding bricks 50 of the intermediate pairs M of the same series of regenerators are operated to open the discharge ends of the vertical air channels 47 and to place them in communication with such regenerators. Accordingly, the opening of the 10 valves of the gas pipes 53 leading to the alternate pairs L of regenerators of the series I' permits the special generator gas to flow into and up through such regenerators. 15 Concurrently, air flows through alternate inlets 44 and thence through the air channels 46 and vertical discharge channels 47 into the intermediate pairs M of regenerators of the series I'. Passing through the 20 top horizontal channels 23 that lead from the regenerators of the series I', supplies of gas and air are delivered to each of the flues of the groups I through the ports 24 of the pairs of channels 23 that communicate with 25 each group I of flues. In the several flues of the groups I the gas ignites in the air and burns downwardly, the waste gases passing into the horizontal channels 33 that are located at the lower ends of said downburning 30 flues. From these channels 33 the waste products flow into the upburning flues of the groups K, which upburning flues are supplied with fresh gas from the horizontal gas channels 32 that are connected by means 35 of the long vertical channels 31 with the top horizontal channels 23 of the alternate pairs L of regenerators of the series I' through which a supply of gas is maintained, as hereinabove explained. The fresh gas which discharges into said upburning flues of the 40 groups K through the ports 34 ignites in the waste gases delivered by the connecting channels 33, said waste gases containing enough uncombined oxygen to support the combustion 45 of the gas in the upburning flues. From the top of the upburning flues, which comprises all the flues of the groups K, the waste gases discharge through the hereinabove described ports 24, then pass into the several 50 top horizontal channels 23 that lead to the several regenerators of the series K. Flowing down through said regenerators of the series K', the waste gases finally discharge through the sole channels 22 and through 55 the open mushroom valves 41 of the flow pipes 39 into the waste gas tunnel 37. On reversal of the battery, by means of the reversing connections hereinabove described, the several regenerators of the series I' 60 operate as outflow regenerators and the sev-

eral flues of the group I as upburning flues at the time the mushroom valves 40 of the flow pipes of such regenerators are open, and the gas supply connections are shut. The mushroom valves 41 of the flow pipes 70 of the inflow operating regenerators of the series K' are closed and the gas valve connections of the intermediate pairs M of such regenerators are open to permit inflow of gas. Air passes into the alternate pairs L 75 of the regenerators of the series K'. The air and gas flows from said regenerators into the downburning flues comprising the groups K, and then into the upburning flues of the group I from which it discharges into 80 the downflow operating regenerators of the series I', it being understood that the operation after reversal is essentially the same as that hereinabove described.

The invention embodies a further mode 85 of operation in that the relatively rich gas derived from the distillation of coal in the retort chambers may be used as the fuel, while simultaneously there is maintained both in the upburning and in the downburning flues a supply of a neutral gaseous diluent, which has the important function of greatly lengthening the flame produced by this relatively rich gas, whether burning up or down, so as to equalize temperature 90 conditions throughout a maximum area of the heating walls and to prevent intense heat concentration in the upper and lower portions of the walls. Because of this heat 95 equalization promoted by the present invention, the heating walls and the intermediate coking chambers may be constructed of great height, without disturbing the factor of heat equalization, while attaining a greatly increased production of coke per 100 unit coking time.

When burning such distillate gas as the fuel for the retort battery, the following is the mode of operation: The supply of the relatively lean gas to the producer gas 110 mains 52 and 54 is turned off and the supply of the relatively rich distillate gas to the mains connected with the gas ducts 26 and 30 is turned on. The sliding bricks 50 and 51 of both series I' and K' of regenerators are adjusted to place all of the regenerators of both said series in communication with the air channels 47 and 49. Assuming that the series I' of regenerators 115 are operating for inflow, the flue groups I for downflow, the flue groups K for upflow and the series K' of regenerators for outflow, the flow through these pairs is as follows: Air enters the several regenerators of the series I' through the air channels 47 and passing upwardly through the heated checkerwork in said regenerators, flows through the channels 23 and is delivered into the downburning flues of the series I, by way of the ports 24. Distillate 120

125 130

gas is supplied to the I groups of flues by means of the gas ducts 26, and said gas flows through the nozzles 27 into the chambers 28 in which it is mixed with supplies of neutral gaseous diluent that passes into said chambers through the ports 35 at the upper end of the vertical diluent supply channels 34 hereinabove described. The waste gas supplied to these channels 34 is derived from the lower ends of the flues 16 of the groups I. The gas admixed with the waste gas diluent ignites in the upper ends of said flues of the groups I and burns downwardly with long flames in said flues. The waste products from the bottoms of the downburning flues pass mainly through the horizontal channels 33 into the bottoms of the upburning flues comprising the groups K. To the lower ends of these upburning flues there is also supplied distillate gas from the bottom gas ducts 30 and additional preheated air from the horizontal channels 32 and the vertical channels 31, which as before mentioned, lead from alternate pairs of regenerators of the series I'. There is thus supplied to the upburning flues from the bottom of the retort battery distillate gas, air and waste gas, with the result that long flames are maintained in the upburning flues. The waste products from the upburning flues pass out through the ports 24 at the top, thence into the channels 28 and downwardly through the several regenerators of the series K', which deliver them to the waste gas tunnel 37. On reversal of the battery the entire series of regenerators K' operate for inflow the flues of the groups K become downburning flues, the flues of the groups I become upburning flues and the entire series of regenerators I' operate for outflow.

The invention as hereinabove set forth is embodied in a particular form of construction but may be variously embodied within the scope of the claims hereinafter made.

I claim:

1. In a vertical retort battery, in combination: a plurality of high narrow retort chambers, each receiving through its top the charge to be coked and discharging through its bottom the coked charge; heating walls contiguous to such retort chambers and respectively constituted of two groups of combustion flues communicably connected together at their lower ends, one group of such combustion flues of each heating wall burning upwardly, while the other group burns downwardly; mixing chambers communicating with the tops of such combustion flues and return waste gas passages connecting the bottoms of such combustion flues with said mixing chambers; fuel gas supply means connected with the aforesaid mixing chambers; fuel gas supply means connected with the bottoms of such combustion flues; two series of high narrow regenerators respectively companion to the upburning and downburning groups of such combustion flues, each series of regenerators being grouped into pairs, the individual members of which are communicably connected with a single companion group of said combustion flues; channels connecting the alternate pairs of regenerators of each series with the other group of such combustion flues; and means for reversing the flow through said regenerators and their connected groups of combustion flues; substantially as specified. 70

2. In a vertical retort battery, in combination: a plurality of high narrow retort chambers, each receiving through its top the charge to be coked and discharging through its bottom the coked charge; heating walls contiguous to such retort chambers and respectively constituted of two groups of combustion flues communicably connected together at their lower ends, one group of such combustion flues of each heating wall burning upwardly, while the other group burns downwardly; mixing chambers communicating with the tops of such combustion flues and return waste gas passages connecting the bottoms of such combustion flues with said mixing chambers; fuel gas supply means connected with the aforesaid mixing chambers; fuel gas supply means connected with the bottoms of such combustion flues; two series of high narrow regenerators respectively companion to the upburning and downburning groups of such combustion flues, each series of regenerators being grouped into pairs, the individual members of which are communicably connected with a single companion group of said combustion flues; channels connecting the alternate pairs of regenerators of each series with the other group of such combustion flues; and means for reversing the flow through said regenerators and their connected groups of combustion flues; substantially as specified. 80

3. In a vertical retort battery, in combination: a plurality of retort chambers, each receiving through its top the charge to be coked and discharging through its bottom the coked charge; heating walls contiguous to such retort chambers and respectively constituted of two groups of combustion flues communicably connected together at their lower ends, one group of such combustion flues of each heating wall burning upwardly, while the other group burns downwardly; mixing chambers communicating with the tops of such combustion flues and return waste gas passages connecting the bottoms of such combustion flues with said mixing chambers; fuel gas supply means connected with the aforesaid mixing chambers; fuel gas supply means connected with the bottoms of such combustion flues; two series of high narrow regenerators respectively companion to the upburning and downburning groups of such combustion flues, each series of regenerators being grouped into pairs, the individual members of which are communicably connected with a single companion group of said combustion flues; channels connecting the alternate pairs of regenerators of each series with the other group of such combustion flues; and means for reversing the flow through said regenerators and their connected groups of combustion flues; substantially as specified. 90

4. In a vertical retort battery, in combination: a plurality of retort chambers, each receiving through its top the charge to be coked and discharging through its bottom the coked charge; heating walls contiguous to such retort chambers and respectively constituted of two groups of combustion flues communicably connected together at their lower ends, one group of such combustion flues of each heating wall burning upwardly, while the other group burns downwardly; mixing chambers communicating with the tops of such combustion flues and return waste gas passages connecting the bottoms of such combustion flues with said mixing chambers; fuel gas supply means connected with the aforesaid mixing chambers; fuel gas supply means connected with the bottoms of such combustion flues; two series of high narrow regenerators respectively companion to the upburning and downburning groups of such combustion flues, each series of regenerators being grouped into pairs, the individual members of which are communicably connected with a single companion group of said combustion flues; channels connecting the alternate pairs of regenerators of each series with the other group of such combustion flues; and means for reversing the flow through said regenerators and their connected groups of combustion flues; substantially as specified. 100

5. In a vertical retort battery, in combination: a plurality of retort chambers, each receiving through its top the charge to be coked and discharging through its bottom the coked charge; heating walls contiguous to such retort chambers and respectively constituted of two groups of combustion flues communicably connected together at their lower ends, one group of such combustion flues of each heating wall burning upwardly, while the other group burns downwardly; mixing chambers communicating with the tops of such combustion flues and return waste gas passages connecting the bottoms of such combustion flues with said mixing chambers; fuel gas supply means connected with the aforesaid mixing chambers; fuel gas supply means connected with the bottoms of such combustion flues; two series of high narrow regenerators respectively companion to the upburning and downburning groups of such combustion flues, each series of regenerators being grouped into pairs, the individual members of which are communicably connected with a single companion group of said combustion flues; channels connecting the alternate pairs of regenerators of each series with the other group of such combustion flues; and means for reversing the flow through said regenerators and their connected groups of combustion flues; substantially as specified. 110

6. In a vertical retort battery, in combination: a plurality of retort chambers, each receiving through its top the charge to be coked and discharging through its bottom the coked charge; heating walls contiguous to such retort chambers and respectively constituted of two groups of combustion flues communicably connected together at their lower ends, one group of such combustion flues of each heating wall burning upwardly, while the other group burns downwardly; mixing chambers communicating with the tops of such combustion flues and return waste gas passages connecting the bottoms of such combustion flues with said mixing chambers; fuel gas supply means connected with the aforesaid mixing chambers; fuel gas supply means connected with the bottoms of such combustion flues; two series of high narrow regenerators respectively companion to the upburning and downburning groups of such combustion flues, each series of regenerators being grouped into pairs, the individual members of which are communicably connected with a single companion group of said combustion flues; channels connecting the alternate pairs of regenerators of each series with the other group of such combustion flues; and means for reversing the flow through said regenerators and their connected groups of combustion flues; substantially as specified. 120

7. In a vertical retort battery, in combination: a plurality of retort chambers, each receiving through its top the charge to be coked and discharging through its bottom the coked charge; heating walls contiguous to such retort chambers and respectively constituted of two groups of combustion flues communicably connected together at their lower ends, one group of such combustion flues of each heating wall burning upwardly, while the other group burns downwardly; mixing chambers communicating with the tops of such combustion flues and return waste gas passages connecting the bottoms of such combustion flues with said mixing chambers; fuel gas supply means connected with the aforesaid mixing chambers; fuel gas supply means connected with the bottoms of such combustion flues; two series of high narrow regenerators respectively companion to the upburning and downburning groups of such combustion flues, each series of regenerators being grouped into pairs, the individual members of which are communicably connected with a single companion group of said combustion flues; channels connecting the alternate pairs of regenerators of each series with the other group of such combustion flues; and means for reversing the flow through said regenerators and their connected groups of combustion flues; substantially as specified. 130

bers; fuel gas supply means connected with the bottoms of such combustion flues; two series of regenerators respectively companion to the upburning and downburning 5 groups of such combustion flues, each series of regenerators being grouped into pairs, the individual members of which are communicably connected with a single companion group of said combustion flues; channels connecting the alternate pairs of regenerators of each series with the other group of such combustion flues; and means for reversing the flow through said regenerators and their connected groups of combustion 10 flues; substantially as specified.

4. In a vertical retort battery, in combination: a plurality of high narrow retort chambers, each receiving through its top the charge to be coked and discharging through 20 its bottom the coked charge; heating walls contiguous to such retort chambers and respectively constituted of two groups of combustion flues communicably connected together at their lower ends, one group of such 25 combustion flues of each heating wall burning upwardly, while the other group burns downwardly; mixing chambers communicating with the tops of such combustion flues and return waste gas passages connecting the bottoms 30 of such combustion flues with said mixing chambers; fuel gas supply means connected with the aforesaid mixing chambers; fuel gas supply means connected with the bottoms of such combustion flues; and two series of high narrow regenerators 35 respectively companion to the upburning and downburning groups of such combustion flues and communicably connected therewith; substantially as specified.

40 5. In a vertical retort battery, in combination: a plurality of retort chambers, each receiving through its top the charge to be coked and discharging through its bottom the coked charge; heating walls contiguous 45 to such retort chambers and respectively constituted of two groups of combustion flues communicably connected together at their lower ends, one group of such combustion flues of each heating wall burning upwardly, while the other group burns downwardly; mixing chambers communicating with the tops of such combustion flues and return waste gas passages connecting the bottoms 50 of such combustion flues with said mixing chambers; fuel gas supply means connected with the bottoms of such combustion flues; and two series of high narrow regenerators 55 respectively companion to the upburning and downburning groups of such combustion flues and communicably connected therewith; substantially as specified.

60 6. In a vertical retort battery, in combination: a plurality of retort chambers,

each receiving through its top the charge to be coked and discharging through its bottom the coked charge; heating walls contiguous to such retort chambers and respectively constituted of upburning and downburning groups of combustion flues communicably connected together at their lower ends; mixing chambers communicating with the tops of said combustion flues and return waste gas passages connecting the bottoms 70 of such combustion flues with said mixing chambers; fuel gas supply means connected with the aforesaid mixing chambers; fuel gas supply means connected with the bottoms of said combustion flues; regenerators 75 respectively companion to the upburning and downburning groups of said combustion flues, some of the regenerators being also communicably connected with the other group of such combustion flues; and means for reversing the flow through said regenerators and their connected groups of combustion flues; substantially as specified.

7. In a vertical retort battery, in combination: a plurality of high narrow retort chambers; heating walls contiguous to such retort chambers and respectively constituted of two groups of combustion flues communicably connected together at their lower ends, one group of such combustion flues of each heating wall burning upwardly, while the other group burns downwardly; mixing chambers communicating with the tops of such combustion flues and return waste gas passages connecting the bottoms of such combustion flues with said mixing chambers; fuel gas supply means connected with the aforesaid mixing chambers; fuel gas supply means connected with the bottoms of such combustion flues; two series of high narrow regenerators 90 respectively companion to the upburning and downburning groups of such combustion flues, each series of regenerators being grouped into pairs, the individual members of which are communicably connected with a single companion group of said combustion flues; channels connecting the alternate pairs of regenerators of each series with the other group of such combustion flues; and means for reversing the flow through said regenerators and their connected groups of combustion flues; substantially as specified.

8. In a vertical retort battery, in combination: a plurality of retort chambers; heating walls contiguous to such retort chambers and respectively constituted of upburning and downburning groups of combustion flues communicably connected together; return waste gas passages connecting the opposite ends of the individual combustion flues; fuel gas supply means also connected with the opposite ends of said combustion flues; regenerators respectively companion to the upburning and downburning groups 100

of such combustion flues, each series of regenerators being grouped into pairs, the individual members of which are communicably connected with a single companion group of said combustion flues; channels connecting the alternate pairs of regenerators of each series with the other group of such combustion flues; and means for reversing the flow through said regenerators and their connected groups of combustion flues; substantially as specified.

9. In a vertical retort battery, in combination: a plurality of retort chambers; heating walls contiguous to such retort chambers and respectively constituted of upburning and downburning groups of combustion flues communicably connected together; return waste gas passages connecting the opposite ends of the individual combustion flues; fuel gas supply means also connected with the opposite ends of said combustion flues; and regenerators companion to and communicably connected with such combustion flues; substantially as specified.

10. In a vertical retort battery, in combination: a plurality of retort chambers, each receiving through its top the charge to be coked and discharging through its bottom the coked charge, heating walls contiguous to such retort chambers and each constituted of both upburning and downburning groups of combustion flues; regenerators respectively companion to the upburning and downburning groups of such combustion flues, each series of regenerators being operable in alternation for inflow and outflow and the inflow operating regenerators comprising both gas and air regenerators, the gas regenerators being communicably connected with both groups of such combustion flues; substantially as specified.

11. In a vertical retort battery, in combination: a plurality of retort chambers, each receiving through its top the charge to be coked and discharging through its bottom the coked charge, heating walls contiguous to such retort chambers and each constituted of both upburning and downburning groups of combustion flues, regenerators respectively companion to the upburning and downburning groups of such combustion flues, each series of regenerators being operable in alternation for inflow and outflow and the inflow operating regenerators comprising both gas and air regenerators; substantially as specified.

12. In a coking retort, in combination: a retort chamber; a heating wall contiguous to such retort chamber and constituted of a combustion flue; a mixing chamber communicating with one end of said combustion flue and a return waste gas passage connecting the other end of said combustion flue with said mixing chamber; fuel gas supply means connected with said mixing chamber;

and means for supplying air to such combustion flue; substantially as specified.

13. In a vertical retort battery, in combination: vertical retort chambers; simultaneously upburning and downburning groups of combustion flues; a fuel gas supply adapted to supply to both groups of flues gas of distillation from the coking chambers; and alternative fuel gas supply adapted to supply to said flues an extraneously derived gas, such as producer gas; and means operable at will for alternatively admitting and shutting off such fuel gas supplies; substantially as specified.

14. In a retort battery, in combination: coking chambers; simultaneously upburning and downburning groups of combustion flues, combined with a regenerative system communicably connected therewith; a fuel gas supply adapted to supply directly to both groups of flues gas of distillation from the coking chambers; and alternative fuel gas supply adapted to supply to some of the regenerators an extraneously derived gas, such as producer gas; and means operable at will for alternatively admitting and shutting off such fuel gas supply; substantially as specified.

15. In a vertical retort battery for the carbonization of coal, in combination: a group of vertical retorts adapted to have the charges pass through them from their top charging-holes to their bottom discharge-openings and having their sides formed by heating-walls constituted of elongated vertical flame-flues adapted to subject the descending charges to flame-heat substantially throughout the height of each retort; paired regenerators arranged alongside the group of retorts and having connections separately communicating with the flame-flues so that the regenerators of each pair may be employed either separately for preheating gas and air or both for preheating air; and supplementary gas-ducts communicating directly with the flame-flues independently of the regenerators and adapted to supply fuel-gas that is not preheated by the regenerators; the aforesaid regenerator connections and supplementary gas-ducts being respectively provided with ports leading into the vertical flame-flues and so distributed that the descending charges in the retorts may be subjected to flame-heat substantially throughout their height irrespective of whether the flame-flues are fired with regeneratively preheated lean gas or with unpreheated rich gas, the ports for air and both kinds of gas being grouped at such plurality of points that flames may be initiated at different levels in the vertical flues.

16. In a vertical retort battery for the carbonization of coal, in combination: a group of vertical retorts adapted to have the

charges pass through them from their top charging-holes to their bottom discharge-openings and having their sides formed by vertically elongated heating-walls constituted of flame-flues adapted to subject the descending charges to flame-heat substantially throughout the height of each retort; paired regenerators arranged alongside the group of retorts and having connections separately 5 communicating with the flame-flues so that the regenerators of each pair may be employed either separately for preheating gas and air or both for preheating air; and supplementary gas-ducts communicating directly with the flame-flues independently of

the regenerators and adapted to supply fuel-gas that is not preheated by the regenerators; the aforesaid regenerator connections and supplementary gas-ducts being respectively provided with ports leading into the 20 flame-flues and so distributed in the vertically elongated heating-walls that the descending charges in the retorts may be subjected to flame-heat substantially throughout their height irrespectively of whether 25 the flame-flues are fired with regeneratively preheated lean gas or with unpreheated rich gas.

JOSEPH VAN ACKEREN.
